UNITED STATES PATENT OFFICE.

ASHMEAD B. CHESTER, OF JACKSONVILLE, ILLINOIS.

DRILL.

Application filed February 28, 1920, Serial No. 362,001. Renewed September 6, 1922. Serial No. 586,537.

To all whom it may concern:

Be it known that I, ASHMEAD B. CHESTER, a citizen of the United States, residing at Jacksonville, in the county of Morgan and 5 State of Illinois, have invented new and useful Improvements in Drills, of which the following is a specification.

This invention relates to a drill and has for its primary object the construction of a 10 device of this character of simple, inexpensive construction, which may be readily connected or disconnected from an operative position.

An object of the invention is to provide a 15 more substantial drill apparatus at less expense.

A feature of my invention is the novel 20 manner of arranging the parts so that the feed screw as well as the drilling mechanism may be operated without the operator changing his position.

With these and other objects in view the 25 invention will be better understood from the following detailed description taken in connection with the accompanying drawing wherein—

Fig. 1 is a side elevation of the apparatus.

Fig. 2 is a detailed view illustrating the rib.

30 Fig. 3 is a sectional view of the bracket.

Fig. 4 is a plan view of the foot.

Again referring to the drawing illustrating one of the many forms in which my invention may be constructed the numeral 1 35 designates a frame having at one end a head 2 supporting the drilling mechanism. The other end of the frame is provided with a tapering dovetail shaped rib 3 for detachable engagement in a correspondingly shaped recess 4 in a bracket or plate 5. This bracket is bolted to a stationary support as indicated at 6. From this construction it will be seen that the frame may be quickly arranged in place and just as readily detached, and by providing a number of brackets at different points in the shop it will be readily seen that the drill may be conveniently used at different points. The

guide bar 7 has its upper end detachably secured to the frame while the lower end is 50 detachably connected to a foot 8. This foot 8 is of a shape and size to bear against the stationary support as indicated at 9 so that in the use of the drill the guide bar 7 will be substantially braced so as to be prevented 55 from being subject to strains. This foot 8 is also provided with a depression 10 for the reception of the lower end of the feed screw 11. This feed screw 11 is reduced so as to form a shoulder 12 engaging a portion 60 of the frame 1 so as to prevent displacement of the screw. A hand wheel 13 is connected to the feed screw for operating the same. Co-operating with the feed screw is a table 14 that is guided in its movement by the 65 bar 7.

It is, of course, to be understood that the invention may be constructed in various other manners and the parts associated in different relations and, therefore, I do not 70 desire to be limited in any manner except as set forth in the claims hereunto appended.

Having thus described my invention what I claim is—

1. In a device of the character described 75 a frame having a tapering dovetail shaped rib, a plate for attaching to a stationary support and having a recess for the reception of said rib, a guide bar having its upper end detachably connected to the frame, and a 80 foot detachably connected to the lower end of the bar and shaped to bear against the stationary support for steadyng the bar.

2. A drill comprising a frame, drilling means arranged at one end of the frame, a 85 bracket having a detachable tongue and groove connection with the frame, a guide bar depending from the frame, a foot screwed to the bar and shaped to bear against the stationary support, a table slidably guided by the bar, and a feed screw for rotatable connection with the frame, a screw thread engagement with the table and having a 90 bearing in said foot.

In testimony whereof I affix my signature. 95
ASHMEAD B. CHESTER.
